HERBERT ALFRED HUMPHREY, OF WESTMINSTER, LONDON, ENGLAND, ASSIGNOR TO
HUMPHREY GAS PUMP COMPANY, A CORPORATION OF NEW YORK.

METHOD OF RAISING OR FORCING LIQUIDS.

1,085,865.

Specification of Letters Patent.

Patented Feb. 3, 1914.

Application filed June 13, 1908. Serial No. 438,427.

To all whom it may concern:

Be it known that I, HERBERT ALFRED HUMPHREY, a subject of the King of Great Britain, residing at 38 Victoria street, 5 Westminster, in the county of London, England, consulting engineer, have invented certain new and useful Improvements in Methods of Raising or Forcing Liquids, of which the following is a specification.

10 My invention relates to improvements in the method of raising or forcing liquid by the expansion of an ignited combustible charge.

The object of the present invention is to 15 provide a method whereby expansions take place in the required order in a plurality of expansion chambers to produce the outward movements or outstrokes of the liquid, the instrokes being due to the pressure or 20 head to which the liquid has moved during the outstrokes. My improved method utilizes the momentum of the said movements 25 in the introduction and compression of successive charges, the introduction of fresh liquid and the expulsion of burnt products.

Referring to the drawings which illustrate, merely by way of example, suitable apparatus for effecting my invention, Figure 1 is a fragmentary section of the combustion chamber end of the apparatus showing the valves and valve gearing. Fig. 2 is a similar view showing a modified form of valve gearing. Fig. 3 is a sectional detail of an electric switch. Fig. 4 is a plan view 35 of same. Fig. 5 is a diagrammatic part plan view of a modified form of apparatus in which the liquid supply pipe branches into two ducts which again join into one discharge pipe. Fig. 6 is a sectional view 40 of a further modification showing an auxiliary liquid supply valve. Fig. 7 is a sectional view of the upper ends of two combustion chambers and associated parts showing modified valve gears and electrical 45 ignition means. Fig. 8 is a view on an enlarged scale of the valves and valve gearing shown in Fig. 1. Fig. 9 is a sectional view through the upper parts of two combustion chambers showing relief valves connecting the same. Fig. 10 is a sectional detail 50 showing dash-pot control for liquid valve 32.

Similar numerals refer to similar parts throughout the several views.

55 In Fig. 1, which is one form of apparatus,

1 and 2 are the combustion chambers shown broken across and much shortened vertically so as to permit the working parts to be drawn to a large scale. The combustion chambers communicate at their lower part 60 with the supply pipe 3 and the discharge pipe 4, the latter being continued to a piece of higher level or higher pressure. At the upper part of the combustion chambers, see also Fig. 8, are fitted admission valves 65 5 and 6 and exhaust valves 7 and 8, and it is sometimes advisable to fit two other valves 9 and 10, the purpose of which will be explained later. The seatings of valves 7, 8, 9 and 10 are shown projecting some 70 distance into the upper part of the combustion chambers with the object of forming a space in the latter in which an elastic cushion can be compressed to prevent shock from liquid which rises in the chambers 75 striking the top of the chambers, and for other purposes presently explained.

The exhaust valves 7 and 8 in the present example open under the action of their own weight, and light springs 11 and 12 serve 80 to limit their motion. On the valve stems are collars 13 and 14, and on the valve plugs are mounted pawls 15 and 16 turning about pivots 17 and 18 and capable of engaging under the collars so as normally to keep 85 the exhaust valves closed. The admission valves 5 and 6, for combustible mixture, open against the action of light springs 19 and 20 which close the valve when the difference of pressure on the two sides of the 90 valve becomes small enough. Admission valve 5 carries on its stem a fixed collar 21 and a pin 43, the former being constructed to engage with pawls 41 and 51 at certain parts of the cycle; the pin engages with one 95 end of bell crank 23. Similarly valve 6 has on its stem a collar 22 capable of engaging with pawls 42 and 52, and also carries a pin 44 which engages with one end of bell crank 24. Bell crank 23 is attached through pin 100 25 to rod 27 the other end of which is pivoted to pawl 16, and bell crank 24 is attached by pin 26 to rod 28 which is pivoted to pawl 15. Thus, when admission valve 5 opens pin 43 on its stem turns bell crank 105 23, causing rod 27 and pawl 16 to be moved to the left, thereby disengaging the latter from collar 14, leaving the exhaust valve 8 free to open. It will be seen that the inlet valve of chamber 1 releases the exhaust 110

valve of chamber 2, and in a similar manner the inlet valve of chamber 2 controls the exhaust valve of chamber 1.

Rod 28 carries a fixed collar 45, a spring 46, and a loose collar 47, and rod 27 carries a corresponding set of parts 48, 49 and 50. A link 53 connects pawls 51 and 52 and is of such length that the pawls cannot be engaged simultaneously with the collars 21 and 22 respectively. Link 53 carries two pins 55 and 56 capable of engaging with collars 47 and 50 respectively in such a way that the movements of rods 27 and 28 may be utilized to move the link 53 and pawls 51 and 52.

Attached to the stem of liquid supply valve 32 is a swivel 33 to which is fastened a rod 34 attached to bell crank 35 turning about pivot 36. This bell crank has a pin and slot connection 37 with rod 38, the other end of which is pivoted at 39 to pawl 42 and connection is carried to the pawl 41 by means of another rod 59 pivoted at 39 and 40. The length of rod 59 is such that pawls 41 and 42 may be simultaneously engaged under the collars 21 and 22. Thus, when liquid supply valve 32 opens, rod 34 is drawn downward and pawls 41 and 42 are moved to the right leaving that admission valve free to open which is not otherwise kept shut by one of the pawls attached to link 53.

The action of the apparatus is as follows: It is assumed that all the valves are in the position shown, that a compressed combustible charge is in the upper portion of chamber 2, and that liquid fills the whole of chamber 1 except for a small space in the top thereof which contains a compressed elastic cushion. Ignition now occurs in chamber 2, and for this purpose a sparking plug 29 is provided in a recess in the admission valve casting. Combustion starts in this recess and spreads past valve 10, so that the whole combustible charge is fired. The rise of pressure drives the liquid in combustion chamber 2 downward and outward from the combustion chamber along the discharge pipe 4. As the two chambers communicate the increased pressure of the liquid in chamber 2 is transmitted to the liquid in chamber 1 and the elastic cushion in the top of chamber 1 is further compressed. As the expansion in chamber 2 continues toward atmospheric pressure a moment arrives when the pressure of the liquid above and below valve 32 is the same, and further expansion causes this valve to open so that liquid from the supply tank 31 (Fig. 2) flows into the apparatus to follow the liquid moving in the discharge pipe. The movement of valve 32 releases pawl 41 from under collar 21 on the stem of admission valve 5. At this time the level of liquid in chamber 2 is lower than the liquid in chamber 1

and the pressure in chamber 2 cannot support the liquid in chamber 1, so that a downward motion of the liquid in chamber 1 occurs, drawing in a fresh combustible charge through the inlet valve 5 and past valve 9, the latter opening automatically under its own weight as soon as the pressure in chamber 1 is relieved. Valve 5 is shut by spring 19 when the charge has been drawn in. The discharge pipe being sufficiently long to permit a considerable portion of the energy of combustion to be transformed into kinetic energy of the outwardly moving column of liquid in the discharge pipe, this column continues to move toward the place of higher level or pressure for some time after the pressure in the combustion chamber has fallen to that represented by the head or pressure to which the liquid is raised, so that expansion may be carried to atmospheric pressure. When admission valve 5 opened to admit the fresh combustible charge into chamber 1 the exhaust valve in chamber 2 was released in a manner already described, consequently when the pressure of expansion is low enough in chamber 2 valve 8 opens and some of the liquid from the supply tank is free to rise in chamber 2 and expel burnt products through the exhaust valve 8. The cycle has now arrived at the point where in chamber 1 there is a fresh combustible charge, the inlet valve 5 and the exhaust valve 7 are shut, and the valve 9 is open. In chamber 2 there are some products of combustion in the upper portion of the chamber, liquid in the lower portion of the chamber, the inlet valve 6 is shut, but the exhaust valve 8 (which opened before valve 5 closed) and valve 10 are open. The outward flow of liquid in the discharge pipe having ceased, an inwardly moving column of liquid commences to flow under the action of its head or pressure. Liquid inlet valve 32 shuts automatically, and the inflowing liquid tends to rise in both chambers but as there is a free outlet for the burnt gases from the top of chamber 2 while there is no outlet for the combustible charge in chamber 1, the returning liquid rises at first only slowly in chamber 1 and more quickly in chamber 2.

When the rising liquid strikes valve 10 and exhaust valve 8, it shuts these valves. Exhaust valve 8 is locked by means of pawl 16 which is pulled into position to engage under collar 14 by spring 58 and valve 10 is held up by the pressure of the rising liquid which compresses the elastic cushion, in this case consisting of a portion of the burnt products inclosed in the top of the chamber. This elastic cushion will expand again to some extent and the pressure will fall somewhat, but neither valve 6 nor valve 8 will open, because the former has been locked by pawl 42 which returned to the

position shown when valve 32 closed, and valve 8 is locked by pawl 16. The flow of liquid into chamber 2 having been checked, the liquid now rises further in chamber 1, compressing the combustible charge therein until the kinetic energy of the column of liquid is expended and the liquid brought to rest, having stored energy in the compressed combustible charge and the compressed elastic cushion. As the volume of the compressed combustible charge is such that the level of liquid in chamber 1 does not reach valve 9, this valve remains open and ignition now occurs by means of a sparking plug 30, and the cycle described commences afresh with the difference that this time the functions of the respective chambers are reversed.

When valve 5 is opened its pin 43 moves bell crank 23, releasing the exhaust valve on chamber 2, collar 50 on rod 27 engages pin 56 on link 53, thus moving this link to the left and compressing spring 49. As valve 5 shuts before valve 8 the collar 14 engaging 26 against the side of pawl 16 keeps rod 27 sufficiently toward the left while valve 5 shuts, and then link 53 completes its movement causing pawl 51 to engage under collar 21, thus locking valve 5 and at the same time 30 releasing pawl 52 from under collar 22. Either of the positions of link 53 is rendered stable by spring 54, which tends to keep link 53 in its lowest position. The spring 57 has a similar function to spring 35 58. These various movements are for the purpose of bringing all the valve gear into the right position for starting the new cycle as mentioned above.

In order that ignition may occur alternately in the two chambers, the movement of link 53 may be utilized to operate a switch, so that when link 53 is to the right ignition plug 29 is in circuit, and when the link is to the left ignition plug 30 is in circuit. The device which causes ignition when the compression pressure has attained its maximum may be of the type described in application No. 411,304.

In Fig. 9, I show relief valves 96 and 97 fitted into the top of the combustion chambers 1 and 2 relief valves which are loaded to blow off at pressures exceeding the explosion pressure, for the purpose of preventing pressures much exceeding the explosion or combustion pressures occurring at the time when, combustion taking place in one chamber forces liquid into the other chamber and further compresses the elastic cushion therein to an extent influenced by the kinetic energy of the liquid which moves under the difference of pressures. The pressure thus attained in the elastic cushion may exceed the combustion pressures. The blow-off from the relief valve may pass 60 either into the external atmosphere or

through a closed pipe into the top of the other chamber as shown; in the latter case there are two such pipes connecting together the tops of the chambers, and each relief valve acts as a non-return valve in its own pipe. The relief valves are of the ordinary type, and need no further description.

Fig. 2 shows the apparatus in a somewhat simplified form, resulting from the omission of that part of the valve gear which is controlled from the liquid supply valve 32 together with link 53 and pawls 51 and 52 shown on Fig. 1, and the action of the apparatus with the simplified gearing will now be described.

As before, it is assumed that the valves are in the position shown and that ignition occurs in combustion chamber 2 followed by expansion, the intake of fresh liquid through valve 32 to follow the liquid moving in the discharge pipe 4, and the intake of a fresh combustible charge in chamber 1 through valves 5 and 9.

When the outwardly moving column of liquid comes to rest and the inward flow of liquid commences, liquid from the supply tank 31 has risen in chamber 2 and valve 32 has shut again. The inwardly moving liquid now rises in chamber 2 expelling the products of combustion through valve 8 which was released by the opening of valve 5, by the action of pin 43, bell crank 23 and link 27 as in the case of Fig. 1. On arriving at valves 8 and 10 the liquid shuts them by impact. Valve 8 is at once locked by pawl 16, but in this construction there is no pawl to lock admission valve 6, consequently, when the products of combustion remaining in the top of chamber 2 are compressed by the rising liquid after valves 8 and 10 are shut, and then these products forming the elastic cushion expand imparting momentum to the liquid so that it falls below the level corresponding with atmospheric pressure, combustible mixture is drawn into chamber 2 through valves 6 and 10, both of these valves being opened by the suction.

The opening of valve 6 releases pawl 15 from under collar 13 on exhaust valve 7, but as the inwardly flowing column of liquid is already compressing the combustible charge in chamber 1 valve 7 does not open and when valve 6 shuts again, pawl 15 again engages under collar 13 and the inwardly flowing liquid now rises in both chambers until maximum compression has been attained in chamber 1 and a fresh cycle is started by the sparking at plug 30 producing ignition. The increased pressure produced by combustion propels the liquid from chamber 1 and causes further compression of the gaseous contents of chamber 2, and the energy stored in both chambers is then utilized in the outward propulsion of liquid. When expansion has proceeded far enough

in chamber 1 the quantity of combustible mixture to make up the required charge is drawn into chamber 2 through valve 6, and the movement of valve 6 withdraws pawl 15 from under collar 13 and this time exhaust valve 7 falls. The inwardly moving column of liquid now drives out the products of combustion from chamber 1 and compresses the combustible charge in chamber 2, and 10 a fresh cycle is started by the ignition of the charge in chamber 2.

In order that ignition may occur alternately in the two chambers there is shown in Fig. 2 a switch 60 capable of being turned 15 into two positions by projections 61 and 62 attached to rods 28 and 27, adapted to engage against switch arms 64 and 65, see Fig. 4. Details of the switch are shown in Figs. 3 and 4. There are four spring contact pieces in two pairs, 67 and 68 constituting one pair and 69 and 70 the other pair. These contact pieces of conducting material are insulated from one another and are so spaced that the two pieces forming one pair 25 may be bridged by a metal tongue 66 carried by switch arm 63 rotating about pivot 71. In Fig. 4 where the parts are drawn in plan, the metal tongue 66 is in a central position and does not make electrical contact with any of the contact pieces, but a small movement in either direction closes the circuit between 67 and 68 or between 69 and 70, thus determining which primary coil of the two ignition coils 91 or 92, see Fig. 7, is 30 to be energized when the ignition device operates the switch which times the ignition.

Valves 9 and 10, which have been referred to in the forms of apparatus described, are not essential to the working of the apparatus 40 but they form a useful part of my invention when high cushioning pressures are used, their object being to prevent liquid rising or splashing into the recess below the admission valve and wetting the sparking plug.

Instead of two combustion chambers placed side by side with a single supply pipe as in Fig. 1, another arrangement is shown in plan in Fig. 5, in which the liquid supply pipe 3 branches into two ducts 3^a and 3^b, one for each of the combustion chambers 1 and 2, and these ducts are continued at 4^a and 4^b to again join into a common discharge pipe 4. In Fig. 5 the ducts on the discharge side are so shaped at their junction that liquid flowing in one duct exercises an inductive action upon liquid flowing in the other duct and vice versa. The effect of this is to develop a suction at an earlier time in that chamber which is to receive a new combustible charge.

When the valves and springs are so constructed and operated that expansion may be carried below atmospheric pressure, the supply tank may be placed at a somewhat lower

level than that shown in Fig. 2, but when fresh liquid is to be raised by suction it is generally preferable to use the automatic change over valve, and such an arrangement will be described with reference to Fig. 6 in which 1 and 2 are the combustion chambers and 133 is the valve which alternately closes communication between the supply pipe 3 and the discharge pipe 4. The action of the apparatus is unaltered so far as the functions of the combustion chambers are concerned, but if valve 133 is in the position shown by full lines, while the pressure produced by combustion in one of the chambers is propelling liquid outwardly along the discharge pipe, a degree of expansion of the burnt products is attained at which the pressures on the two sides of valve 133 become equal and any further lowering of pressure in the chamber causes valve 133 to take up the dotted position, so closing communication between the chambers and the discharge pipe, and owing to its kinetic energy the moving column of liquid in the discharge pipe can draw liquid from a low level auxiliary supply tank through the auxiliary liquid supply valve 134. Liquid from the supply tank 31 now passes through supply pipe 3 and rises in that chamber from which the burnt products are to be expelled. When, after the working stroke, a column of liquid begins to move inwardly, liquid supply valve 134, shuts automatically and valve 133 is forced from the dotted position to the position shown in full lines, thus permitting the inwardly moving column of liquid on the discharge side to expel the burnt products from one chamber and compress the fresh combustible charge in the other chamber.

When valve 133 closes communication between the chambers and the discharge pipe, the liquid in the latter is moving with considerable velocity, while the liquid in pipe 144 is at rest and has to be accelerated to follow the liquid moving in the discharge pipe. To prevent the formation of a vacuum, and subsequent shock, a small spring-controlled valve 143 is fitted to admit air, and so provide an elastic cushion, this air being drawn in while the liquid in pipe 144 is being accelerated. By adjusting the tension of the spring on valve 143, the amount of air admitted can be controlled, or the amount of air admitted may be controlled by other equivalent means.

Any of the liquid supply valves such as valve 32, in Figs. 1, 2 and 5, or valve 133, or valve 134 in Fig. 6, may be held open or retarded in the closing by any suitable retarding means. In Fig. 10, I show a dash-pot control for valve 32. The rod 98 connected with valve 32 is provided with the piston 99 operating in the dash-pot cylinder 100, which is filled with oil. The non-return

valves 101 in piston 99 allow the oil to pass from the underside to the upper side of the piston, thus permitting the valve 32 to open freely. The shutting of the valve can only 5 take place by forcing the oil from the upper side of the piston to the under side through the by-pass 102 controlled by the cock 103. By means of which the amount of retardation of the valve in closing, can be regulated.

10 The greater the retardation, the higher the velocity of escape past valve 32, before the valve closes, and therefore the higher the pressure of compression. Another result may be that the liquid which leaves the supply tank 31 in Fig. 6 at each cycle is equal 15 in quantity to the liquid which re-enters the supply tank at each cycle, so that the whole of the liquid discharged may be equal in quantity to that supplied through the liquid supply valve 134.

20 It is obvious that certain features of method and apparatus described in my co-pending application No. 438,425, filed June 13, 1908, may be utilized in the present invention, for example, the increased velocity 25 of the inwardly moving column may be utilized to expel a combustible charge which has failed to ignite, and bring about the introduction of another combustible charge at the expense of the energy of liquid which falls from a higher to a lower level, thus 30 keeping the cycle of operations going until a working stroke is obtained. This is specially useful when starting the apparatus to 35 work.

40 A portion of the energy of each charge may also be used to raise liquid into the apparatus or to introduce a fresh combustible charge or a constituent thereof. The fact 45 that there are two combustion chambers instead of one does not alter the order in which the inwardly and outwardly flowing columns of liquid move, or the relation of such movements to the movement of liquid which enters the apparatus from the supply side.

What I claim is:—

1. The method which consists in reciprocating liquid, one movement or outstroke of said liquid being due to the expansion of a 50 combustible charge in one of a plurality of expansion chambers connected together, utilizing the kinetic energy of return stroke of the liquid to expel burnt products from one chamber and compress a fresh expansible charge in another chamber in the same cycle.

2. The method which consists in reciprocating liquid, one movement or outstroke of said liquid being due to the expansion of a 55 combustible charge in one of a plurality of expansion chambers connected together, utilizing the kinetic energy of return stroke of the liquid to expel burnt products from one chamber and compress a fresh expansible charge in another chamber in the same

cycle, and utilizing the kinetic energy of an outstroke to introduce a fresh expansible charge.

3. The method which consists in reciprocating liquid, an outstroke due to an expansive force, utilizing kinetic energy of the instroke to compress a fresh expansible charge in one region of expansion and to expel burnt products from another, utilizing the kinetic energy of the outstroke to cause 70 a diminution of pressure to entrain a fresh charge into one region of expansion. 75

4. The method which consists in reciprocating liquid, an outstroke due to the expansion of a combustible charge in one of a plurality of regions of expansion, utilizing the kinetic energy of the return stroke to compress a fresh combustible charge in another region of expansion and to expel 80 burnt products from the first region of expansion, utilizing the kinetic energy of one outstroke to introduce part of a fresh combustible charge and utilizing the kinetic energy of another outstroke due to the expansion of an elastic cushion in one region 85 of expansion to introduce the balance of the combustible charge. 90

5. The method which consists in reciprocating liquid by expansible charges expanding alternately in different regions of expansion, utilizing the kinetic energy of the outstroke of the liquid to introduce fresh charges and also fresh liquid and utilizing the kinetic energy of the instroke of the liquid to compress a fresh combustible charge 100 in one region of expansion and to expel burnt products from another region of expansion during the same cycle of operation. 105

6. The method which consists in reciprocating liquid, one movement of said reciprocation being an outstroke due to an expansive force exerted in one of a plurality of regions of expansion, utilizing the kinetic energy of the outstroke, after communication between the moving liquid and the region of expansion is interrupted, for entraining fresh liquid. 110

7. The method which consists in reciprocating liquid, an outstroke being due to an expansive force exerted in one of a plurality 115 of regions of expansion, utilizing the kinetic energy of a return flow to compress a fresh combustible charge in a second region of expansion and expel burnt products from the first region of expansion, allowing the liquid propelled from one region of expansion to exert an inductive action on liquid communicating with the other region. 120

8. The method which consists in reciprocating liquid, an outstroke due to an expansive force exerted in one of a plurality of regions of expansions, utilizing the kinetic energy of the instroke of each cycle to compress an expansible charge in one region of expansion and to expel burnt products from 125 130

another region of expansion, and permitting the liquid to run to waste during the first part of the instroke to increase the kinetic energy.

5. 9. The method which consists in reciprocating liquid, the first movement or out-stroke due to an expansive force exerted in one of a plurality of regions of expansion, utilizing the momentum of the instroke to 10. compress an expansible charge in one region of expansion and to expel burnt prod-

ucts from another region of expansion, at each cycle, and permitting the escape from the several regions of expansion of pressures beyond a predetermined maximum. 15

In testimony whereof I have signed my name to this specification in the presence of two subscribing witnesses.
